LOCKED-IN-MESH-RACK-AND-PINION
MECHANISM FOR TYPEWRITER

John E. Finch, Sr., Jersey City, N. J.

Application November 25, 1953, Serial No. 394,403

14 Claims. (Cl. 197—96)

My invention relates to an improvement in typewriter machines, and more particularly to an improved "locked in mesh" rack and pinion mechanism for typewriters.

It is an object of my invention to mechanically lock the rack in its proper depth of mesh with the pinion on that type of typewriter which employs a disengaging rack, rather than depending upon a spring or springs to maintain mesh as heretofore, thereby to effect a smoother carriage movement during typewriting.

Another object of the present invention is to bring about the release of the rack from the lock when the tabulator key or rack release lever is depressed.

Another object of my invention is to assure a more positive and uniform left margin to the writing by preventing either whole or partial rack lift from pinion mesh due to impact on return of the carriage to the left margin stop, whether return be made manually or by power.

Another object of this invention is to assure a more positive and uniform tabulation by dropping the rack into instant locked mesh with the pinion, when the tabulation point has been reached by the carriage.

Another object of this invention is to make possible the use of obliquely cut or various other shapings of rack and pinion teeth, with the object of reducing carriage vibration, not presently feasible with a disengaging rack, due to the likelihood of disengagement skip.

Still another object of my invention is to greatly reduce wear on the teeth of a rack and pinion in the typewriter.

Other objects and features of this invention will become apparent from the accompanying detailed description taken in conjunction with my accompanying drawings wherein:

Fig. 1 is an end or side view of a typewriter machine taken on line 1—1 of Fig. 2 and embodying a preferred form of my invention;

Fig. 2 is a broken away top plan view of a typewriter machine with a carriage mechanism embodying my invention;

Fig. 3 is a section of a detail taken on line 3—3 of Fig. 2;

Fig. 4 is a section taken on line 4—4 of Fig. 2;

Fig. 5 is a fragmental vertical elevation taken on line 5—5 of Fig. 2;

Fig. 6 is a section taken on line 6—6 of Fig. 2;

Fig. 7 is a fragmental view showing a modification of Figs. 3 and 4 of a toggle lock design as embodied in my invention;

Fig. 8 is a side view of Fig. 7; and

Fig. 9 is a fragmental detail modification of the view shown in Fig. 7.

Referring now to the drawings wherein similar reference characters denote like parts throughout, it will be noted that in a typewriter machine 10 of the usual or conventional type, I show on the carriage mechanism 11 a rack 12 secured to a rack bail frame 13, said carriage having carriage ends 11a as shown in Figs. 2 and 6.

In order to insure locking engagement of said rack

2

and the pinion 16 to eliminate the possibility of disengagement skip, and to minimize vibration and jarring, I provide at the top flat surface 20 of the escapement frame or unit 18 which, as shown, is at an incline toward the front of the typewriter 10, an L-shaped post 21. Near the top of said post is a threaded opening for an eccentric or off-center shoulder screw 22 with a threaded end long enough to project through the matching thread opening and to be secured in position when properly adjusted for lock-arm position above rack bail upper surface 13a by a lock nut 22a.

Said shoulder screw 22 when inserted in post 21 is parallel with and disposed directly over the back edge of the carriage rack bail frame 13. Said shoulder screw 22 has attached to it and suspended from it a rack lock arm 23 and is provided with a tension coil spring 24 which is shaped and applied to the lock arm to hold it normally in its forward or locking position, as shown in Fig. 3. Said lock arm 23 is notched at its lower end so that it fits over and behind the rear upper edge of the carriage rack bail frame.

Furthermore, said arm is provided with a roller bearing 25 to facilitate sliding movement of the rack bail frame and to avoid carriage bind or drag.

Furthermore, said arm is notched at its upper end to limit against an extension 21a at the top of post 21 in order to maintain a slight clearance of notched lock arm bottom 26 from the rear edge of the rack bail frame top and to avoid a drag on carriage travel.

Spring 24, as shown, is fixed at one end to post 21 and at its other end to rack lock arm 23 to effect a positive cover of notched end 26 over the upper surface of the rack bail frame.

The arm 23 as constructed will insure a positive mesh of the rack 12 and the pinion 16 teeth during the typing operation since the rack, which is secured to the rack bail frame, cannot lift from engagement with the pinion.

In order to allow for the release of the rack by the rack release levers 27 or by the tabulator rack lift lever 35 of the tabulator mechanism, not shown, I provide a rack lock release cross rod 29 which hangs parallel with and above the top section of the rack bail frame 13, and is secured to end bar members 30 which are in pivotal connection with the rack release lever extension 27a.

It will be noted that said rod is set above the rack bail frame only sufficiently high to allow for its proper lift when unlocked. Its normal position, as shown in Figs. 4 and 6, is just forward of the lower part of the lock arm 23.

Said rod 29 forms the cross member of a hanging bail which as above indicated has the offset arms 30 attached which reach upward to and are suspended from around pins or headless screws 31 which act as bearings. It will be noted that these pins 31 also carry spacing collars 31a outside of the bail arms 30 to give said bail arms working clearance from presently existing mechanisms inside and near the carriage ends, as shown.

Said arms 30 are also provided with openings 30a as shown for hooking the links 32 thereto. Said links are hooked at their other ends and are connected in small openings 27b in extensions 27a of the rack release levers 27.

Said release levers as will be seen, ride just outside of the carriage ends 11a, while the extensions 27a are curved downwardly fitting inside existing slots in the carriage ends, said slots having been enlarged so that the extensions can connect with the rack lock release bail arms 30, inside of the carriage ends.

Adapted to contact said rod 29 is a claw member 33 which is pivotally mounted onto an extension 34 of the tabulator rack lift lever 35. Said claw 33 is provided

with a light tensioned retaining spring 36 to normally keep the claw over rod 29 to prevent it from losing the functioning position with respect to actuating the rack lock release cross rod 29. The rack lift lever 35 is in connection with the tabulator mechanism, not shown, and functions to lift the rack bail frame 13 when the end 38 of the rack lift lever 35 is operated and moved in the direction of the lowermost arrow shown in Fig. 4. The pinion 16 is operatively associated with the star wheel 36a whose teeth 37 cooperate with one or more conventional escapement dogs, not shown.

In operation, when one of the rack release levers 27 is depressed, it swings in a forward and downward arc. The same happens to its extensions 27a beneath and to the front of the rack lock release bail arms 30. Since the extensions 27a are connected to the upper parts of the bail arms 30 by links 32, above and slightly forward of the bearings 31, when the rack release lever is depressed, the lower ends of the bail arms carrying the release cross rod 29 are forced rearwardly, and the release rod moves against the rack lock arm 23 just before the rack lifts, thus releasing the rack for lift. Timing adjustment is made by forming the links 32.

Since the tabulator rack lift lever 35 moves when in operation in an arc opposite to that of the rack release levers and from the rear of the lock arm release claw 33, said claw pulls the rod against the lock arm 23 to free the rack for lift when the tabulator mechanism is employed.

In the modification shown in Figs. 7 and 8, it will be noted that I provide a rack lock 39, wherein there is a rigid arm 40 and a movable arm 41 pivoted to post 21. Between said arms is a tension spring 42 to hold said arms normally together in a locking position. Beneath said arms and in substantially the same plane thereof are a pair of arms 43 and 44 connected pivotally to the other arms thus forming a toggle lock design.

It will be noted that said arms are provided with stops 45 and 46 for the arms 40 and 41, respectively. Also, arm 43 is provided with a lock 47 whereby rod 29 is retained in position between arms 43 and 44 when the rack lock is in operation. Furthermore, said arm 43 is provided with a bifurcated extension 48 accommodating a roller bearing 49, which normally rides on the upper surface of the rack bail frame.

In Fig. 9 there is shown a further modification of the rack lock assembly with a toggle action. A post 21a is provided with an L-shaped arm 50 which is fixed thereto. Pivoted to one end of the arm 50 is a downwardly extending arm 51 pivoted to arm 51a having a bifurcation 52 accommodating a roller bearing 53 for contact on the upper surface of rack bail 13.

Pivoted to said arm 51a and at the lower end thereof is another arm 54. It will be noted that said arm 54 is thus pivoted at each of its ends to arms 50 and 51a respectively. Furthermore, said arm 51a has a widened portion so that with arm 54 they accommodate rod 29 in a manner similar to the embodiment shown in Fig. 7. The arms 50 and 51 are normally urged together about their pivots by means of tension spring 55.

The presently existent back space rack lock, not shown, reset for a light contact with the top of the release rod 29 when back-spacing has been retained merely to act as a brake on the carriage back-travel and to prevent overthrow, the rack lock function having been accomplished as described.

It will be noted that the rack lock post 21 is placed on the top of the escapement frame 18 where the small carriage roll extension was formerly placed. In addition, I have provided a toggle lock for the rack instead of the rigid lock arm, as shown in Figs. 3 and 5.

While preferred embodiments have been illustrated and described, it is to be understood that modifications as to form, arrangement and use of parts may be made without departing from the spirit and scope of the invention as claimed.

What I claim is:

1. In a typewriter machine, a rack and pinion, a post member extending upwardly of the machine, locking means pivoted to the member for contacting said rack, a tabulator rack lift lever, a claw member pivoted to the lever, and a rack lock release cross rod operable by said claw member to release the locking means upon actuation of the rack lift lever.
2. In a typewriter machine, a post member, a rack lock arm pivoted to the post member, a rack bail frame, a rack on said frame, a pinion for said rack, a rack release lever, a bail arm operable by the rack release lever, a release cross rod in connection with the bail arm adapted to move against the rack lock arm, a rack lift lever, means on said rack lift lever for actuating the cross rod, and means for operating the rack lift lever.
3. A typewriter machine according to claim 2, wherein the rack lock arm is tiltable and adapted to abut against the post member and has a recessed lower portion adapted to swing against the longitudinal edge of the rack and against the top thereof to keep the rack bail frame in firmly engaged position with the pinion during operation of the machine.
4. A typewriter machine according to claim 2 wherein in said lock arm on the post is under tension and is provided with bearing means for sliding contact with the rack bail frame.
5. A typewriter machine according to claim 2 wherein the means on said rack lift lever is a downwardly tensioned claw member overlapping and contacting the cross rod.
6. A typewriter machine according to claim 2 wherein the rack lock arm is a toggle unit pivoted from the post member and is adapted to lock hold the cross rod.
7. A typewriter machine according to claim 6 wherein the toggle unit comprises a pair of tensioned upper arm members pivoted to said post and a lower pair pivoted to the upper pair and engaging the cross rod, one of the lower arm members carrying bearing means for sliding contact on the rack bail frame.
8. In a typewriter machine, an improved locked-in mesh rack and pinion mechanism, comprising a rack and pinion, a pair of spaced depressible rack release levers, a pair of spaced bail arms operable by the levers, a lock release cross rod held by said bail arms, a rack bail frame beneath said cross rod, said bail arms forming contact with the rack bail frame, a post, pivotal means extending from the post adapted to make sliding contact with the rack bail frame, a lift lever, and means operable by the lift lever adapted to engage and actuate the cross rod.
9. An improved mechanism according to claim 8, wherein the means adapted to engage and actuate the cross rod is mounted on the lift lever and comprises a pivoted, tensioned extension member in the shape of a claw member for grasping the cross rod.
10. In a typewriting machine having a rack and pinion, an improved rack and pinion mesh-locking device comprising a post member extending upwardly of the machine, toggle locking means secured to the member for contacting said rack to hold the rack and pinion in relatively fixed position, a rack lock release cross rod, and means for actuating the cross rod to release said toggle locking means.
11. In a typewriting machine having carriage ends, a rack body and a pinion normally in mesh therewith, a post member, a rack lock arm pivoted to the post member, a pair of bail arms, a rack lock release cross rod secured to and supported by said bail arms, said bail arms being pivoted within the carriage ends and adapted to move the rod against the rack lock arm, a pair of rack release levers, extensions to said rack release levers connected to said rack lock release bail arms for actuation of the rack lock release bail arms and rod, a tabulator rack lifting device and an extending member on the tabulator

lator rack lifting device for actuation of the rack lock release cross rod.

12. A typewriting machine according to claim 11 wherein the rack lock arm is a toggle unit secured to the post member and adapted to retain the rack lock release cross rod.

13. A typewriting machine according to claim 12, wherein the toggle unit comprises a pair of coil spring connected upper arm members, one of which is rigidly and one pivotally secured to the post member, and a lower pair pivoted to the upper pair and retaining the cross rod, one of the lower arm members carrying bearing means for sliding contact on the upper surface of the rack body.

14. In a typewriting machine having a toggle lock and a rack and pinion locked in mesh thereby, said toggle lock

5

10

including lower toggle arms, a pair of spaced depressible rack release levers with added extensions, a pair of spaced bail arms, hooked heavy wire links connecting said rack release lever extensions with the bail arms, and a lock release cross rod held normally by said bail arms in light contact with the inner edges of the lower toggle arms, said light contact being obtained by centering said cross rod between said lower toggle arms and by the formation of said hooked heavy wire links connecting said rack release lever extensions with the bail arms, the toggle lock of the rack being released by actuation of said cross rod.
